UNITED STATES PATENT OFFICE.

EDWARD R. SARGENT, OF NEW HAVEN, CONNECTICUT, ASSIGNOR TO THE SARGENT & COMPANY, OF SAME PLACE.

BOX-FASTENER.

SPECIFICATION forming part of Letters Patent No. 614,181, dated November 15, 1898.

Application filed February 9, 1898. Serial No. 669,683. (No model.)

To all whom it may concern:

Be it known that I, EDWARD R. SARGENT, of the city and county of New Haven, in the State of Connecticut, have invented a new and useful Improvement in Box-Fasteners, of which the following is a full, clear, and exact description, taken in connection with the accompanying drawings, which form a part thereof, and in which—

10 Figure 1 represents a box-fastener embodying my invention as applied to the lid of a box shown in side elevation and in its locked position. Fig. 2 is a similar view of the catch itself when in its open position; and Figs. 15 3 and 4, a horizontal and a vertical section through the catch on lines 3 3 and 4 4 of Fig. 1, respectively.

In all figures similar letters of reference represent like parts.

20 This invention relates to fasteners for boxes, and is more particularly applicable to boxes the covers of which are not hinged, but adapted to slide, as in the case of the outside boxes for caskets, &c.

25 The invention consists more particularly in the novel construction of the catch which holds the lid against longitudinal movement and combination of parts contained therein hereinafter set forth and claimed.

30 In the drawings, A represents a portion of one side of a box, and a its lid. Into the box A are driven or otherwise secured two staples B and B', while a flat L-shaped hook C is attached to the lid a and adapted to engage 35 with the staple B' and hold the end of the lid near which it is placed from being raised. The lid may, however, obviously be released by sliding it horizontally to the right, Fig. 1.

The catch, which is secured by screws or 40 other means to the lid a near its other end, is formed of two plates, one of which, the stationary or base plate D, is provided with two lateral extensions d, adapted to form on opposite sides the barbs or bights for engagement with the staple B and with a vertical slot d'. The second or movable plate E is also provided with oppositely-extending lateral projections e, on the under side of which are shoulders e', which constitute hooks or

50 catches, while beyond the shoulders e' the lower edge of the plate is beveled, as shown at e² in Figs. 1 and 2. The plate E is made U-shaped along its central line to form a socket F with the base-plate D, while on its lower and upper ends are lips or flanges f and 55 f', turned inward to close the ends of the socket F. The flange f is equal in length to the depth of the socket F, (see Fig. 4,) while the flange f' is slightly longer to project into the slot d'. On the face of the plate E is a 60 slot or opening e³ into the interior of the socket, and a stud G projects therethrough and is secured to the base-plate D.

A spring H is fitted into the socket F between the flange f and stud G and normally 65 tends to force the plate E downward on the plate D until the movement of the plate E is checked by the stud in the slot e³ or the flange f in the slot d. When the plate E is in this its normal position, the outer ends 70 of the beveled surfaces e² are above the lower edge of the bights d, as shown in Fig. 1, so that any pressure exerted by the staple along the lower edge of the rigid or base plate D will tend to raise the outer plate E against 75 the tension of the spring until the shoulder e is reached, when the spring will force the plate E downward and the shoulder engage and securely lock the staple. To relieve the 80 staple, pressure on the lower end of the plate E raises it, and as this movable plate is on the outside there is no difficulty in reaching it nor necessity of placing the finger in any slot or opening to operate the latch.

The plate E is guided in its movement at 85 two points, (where the flange f' extends into the slot d' and where the stud G projects through opening e³,) and therefore is limited strictly to a vertical movement and prevented from any tendency to rotate if the pressure is exerted at one side or the other of the central line.

The two bights allow the device to be used either as a right or left hand catch, and the whole tool being composed of substantially 95 but two pieces of sheet metal with a spring is readily manufactured and assembled with a minimum expenditure of labor or cost.

Having now described my invention, which may vary without departing from the spirit thereof, what I claim, and desire to secure by Letters Patent, is—

- 5 1. A box-fastener consisting of an inner plate adapted to be secured to the box-lid or other article, having a laterally-projecting hook; an outer plate mounted on said inner plate having a lateral projection provided with a catch and a centrally-disposed socket, said outer plate being secured to said inner plate so that it is capable of only a limited vertical movement thereon; a spring located in said socket constantly tending to force said outer plate downward on said inner plate; and mechanism on said box or other article adapted to be engaged by said hook and held in engagement by said catch, substantially as described.
- 10 2. A box-fastener consisting of an inner

plate adapted to be secured to the box-lid or other article having oppositely-projecting lateral hooks; an outer plate having similarly-disposed projections provided with catches, and a centrally-located socket, said outer plate being mounted on and secured to said inner plate so that it is capable of only a limited vertical movement thereon; a spring located in said socket tending to force said outer plate downward on said inner plate; and mechanism on said box or other article adapted to be engaged by said hook and held in engagement by said catch, substantially as described.

In witness whereof I have hereunto set my hand this 8th day of February, A. D., 1898.

EDWARD R. SARGENT.
